UNITED STATES PATENT OFFICE.

WILHELM HOPF, OF KIEL, GERMANY, ASSIGNOR TO FRIED. KRUPP AKTIENGESELLSCHAFT GERMANIAWERFT, OF KIEL-GAARDEN, GERMANY.

WATER-TUBE BOILER.

1,162,063.

Specification of Letters Patent. Patented Nov. 30, 1915.

Application filed December 21, 1911. Serial No. 667,183.

To all whom it may concern:

Be it known that I, WILHELM HOPF, a citizen of the German Empire, residing at Kiel, Germany, have invented certain new and useful Improvements in Water-Tube Boilers, of which the following is a specification.

This invention relates to that class of water tube boilers which are fitted for working under artificial draft and which comprise at least one upper boiler and one lower boiler and nests of tubes connecting them, such nests of tubes being subdivided by products of combustion or heating gas guide walls or baffles which latter form a number of heating flues. In boiler plants of this class, the chimneys or uptake pipes are mostly of only small dimensions, while the resistance opposed to the heating gases inside the boiler are comparatively great even when the artificial draft is taken into consideration. In consequence thereof when the artificial draft is shut off the natural chimney draft is, as a rule, only sufficient for quite small boiler outputs, so that even with a slightly increased consumption of steam the fan has to be set going. As in such cases the fan is not used to its full extent, its effective action is only small, and the working costs expended are not in adequate proportion to the output of the boiler.

The object of this invention therefore, is to provide a water tube boiler of the kind hereinbefore mentioned which has not the disadvantages above mentioned.

Three constructional forms of the subject matter of the invention are illustrated by way of example in the drawing, in which—
Figure 1 is a longitudinal vertical section 40 of a water tube boiler with three upper boilers, two lower boilers, and a superheater. Fig. 2 is a view, corresponding to Fig. 1, of a water tube boiler with two upper boilers and one lower boiler, and Fig. 3 is a similar 45 view of a water tube boiler with one upper and one lower boiler.

The constructional form shown in Fig. 1 will be described first.

The boiler consists of three upper boilers 50 A A' and two lower boilers C, connected thereto by four nests of tubes B B'. Between the two lower boilers C is placed the furnace D. Between the nests of tubes B and B' is arranged a superheater E, between each of

55 which latter and the furnace chamber is

placed a valve G, by means of which each superheater can be thrown into, and out of action. Into the groups of tubes B are built heating gas guide walls or baffles F F' of some fire proof material, such as fire clay or the like, said guide walls consisting of parts F which run longitudinally of the nests of tubes B, and may if necessary be formed also of tube walls, and of short parts F' lying at, or substantially at right angles thereto.

On the inner side of the nests of tubes B' are provided heating gas guide walls F², which are carried under the superheater E and up, adjacent to the nests of tubes B, in the shape of a U. On the outside, each nest of tubes B' is closed in by a heating gas guide wall F³, which does not extend quite up to the upper boilers A', and not quite down to the lower boilers C. At the lower ends of the guide walls F³, are pivoted valves J, which in one extreme position lie against the lower boilers C, and in the other extreme position lie against the surrounding masonry H. Outside the guide walls F³ between them and the surrounding masonry H, are formed heating flues K.

When the above described boiler is worked under artificial draft, the valves J are brought into the position shown by full lines in Fig. 1. The heating gases then first pass through the part of the nests of tubes B lying inside the guide walls F F', then (after passing through the superheater, if necessary) into the part of the nests of tubes B lying outside the heating gas wall F F', and afterward pursue their course, guided by the heating gas walls F², F³, through the nests B', and through the outer flue K into the chimney. If on the other hand the boiler has only to generate a small quantity of steam, in which case it is not profitable to set the fan going, the nests of tubes B', and the flues K, can be cut out by placing the valves J in the position indicated by dotted lines in Fig. 1. The heating gases then pass through the nests of tubes B only, and then through the valve openings J direct to the chimney. In this way the resistance inside the furnace is naturally considerably reduced, and an efficient utilization of the remaining part of the boiler can be secured, even with a small chimney.

The boiler shown in Fig. 2, consists of

two upper boilers A, A¹, and a lower boiler C connected thereto by nests of tubes B, B¹ and shows practically the left hand half of the boiler shown in Fig. 1. It also differs 5 from the boiler first described by the heating gas guide wall F² being arranged within the nest of tubes B¹, so that a portion of the tubes of this nest always lies in the heating gas flue K. A slide valve J is also provided, instead of a pivoted valve, for cutting out the nest B¹, when working under natural draft.

Finally in the constructional form shown in Fig. 3, the boiler consists of only one 15 upper boiler A, and one lower boiler C, which are connected with each other by a nest of tubes B. This latter nest B is divided by two heating gas guide walls F, F¹, thus forming three flues, and the outside flue 20 of these three flues can be cut out by opening a slide J, when working with natural chimney draft.

In the boilers shown in Figs. 1 and 2 the 25 valve or slide J is placed at a point at which fine cinders easily collect. The advantage of this is that when the valve or slide is opened the fine cinders are carried along into the chimney.

I claim:—

30 1. In water tube boilers having at least one upper and one lower drum, the combi-

nation of nests of tubes connecting said drums, baffle walls inserted in said nests in the length direction of the tubes, and gates adjacent the chimney and forming continuations of said baffle walls when closed, whereby the heating flue will be directed through all the nests in opposite direction on the opposite sides of said walls, and said flue guided direct to the chimney when said gates are open; thereby excluding the tubes nearest the chimney from the heating flue. 35

2. In water tube boilers having at least one upper and one lower drum, the combination of nests of tubes connecting said drums, baffle walls inserted in said nests in the length direction of the tubes and gates adjacent the chimney and forming continuations of said baffle walls when closed, whereby the heating flue will be directed 40 through the nests in opposite direction on opposite sides of said walls, said gates being situated at such points of the flues where fine cinder is apt to collect and, when open, to exclude the tubes nearest the chimney 45 from the heating flue. 50

In testimony whereof I have affixed my signature in presence of two witnesses,

WILLIEM HOFF.
